US00D707067S

(12) **United States Design Patent**
Basarich et al.

(10) **Patent No.:** **US D707,067 S**
(45) **Date of Patent:** **** Jun. 17, 2014**

(54) **ADJUSTABLE SHELF**

(71) Applicant: **L.A. Darling Company**, Paragould, AR (US)

(72) Inventors: **Kyle Basarich**, Brookland, AR (US); **Gregory O. C. Ota**, Jonesboro, AR (US); **John Dealy**, Jonesboro, AR (US)

(73) Assignee: **L.A. Darling Company**, Paragould, AR (US)

(**) Term: **14 Years**

(21) Appl. No.: **29/467,015**

(22) Filed: **Sep. 13, 2013**

(51) **LOC (10) Cl.** **06-06**

(52) **U.S. Cl.**

USPC **D6/705**

(58) **Field of Classification Search**

USPC D6/396-397, 418, 449, 511, 513, D6/572-574, 672, 705; 211/71.01, 88.01, 211/90.01, 126, 134, 153, 193; 108/106, 108/137, 157.1, 159.1, 180
